UNITED STATES PATENT OFFICE.

EDWIN E. SLICK, OF JOHNSTOWN, PENNSYLVANIA.

METHOD OF MAKING RETURN L'S.

Application filed September 26, 1919. Serial No. 326,625.

To all whom it may concern:

Be it known that I, EDWIN E. SLICK, a citizen of the United States, residing at Johnstown, in the county of Cambria and State of Pennsylvania, have invented a new and useful Improvement in Methods of Making Return L's, of which the following is a full, clear, and exact description, reference being had to the accompanying drawings, forming part of this specification, in which:—

Figure 1 is a longitudinal section through a piece of tubing to be used in making the L;

Figure 2 is a section through the die showing the piece of tubing about to be distorted or bulged;

Figure 3 is a similar section at the completion of this operation;

Figure 4 is a section through the L after it has been bent into U-shape; and

Figure 5 is a section showing the completed product.

The present invention relates to forged metal return L's and the method of making the same. By return L is meant a U-shaped pipe fitting in which two pipes are secured to get a reversal of direction. My improved return L is entirely seamless and formed by a forging operation. Referring to the drawings, a short length 2 of seamless tubing is the material which is forged into the return L. As shown in Figure 1 the ends of the length of the tubing are cut obliquely or on the bias, so as to give an excess of metal at that side of the tubing which is later bulged outwardly. The length of the seamless tubing 2 is brought to a forging heat and placed between two dies 3 and 4. The die 4 has a semi-cylindrical channel, while the die 3 has a semi-cylindrical channel with a cup-shaped opening 5 therein. Two plungers 6 and 7 act on the pipe length 2 as held between the dies 3 and 4. Each plunger has a rounded nose 8 which enters the tube 2 and an annular shoulder 9 which engages the end of the tube 2. The plungers 6 and 7 are moved from the position shown in Figure 2 to that shown in Figure 3, causing the tube 2 to bulge out into the cavity 5 forming a hollow bulge or projection 10 in one side of the tube 2. This bulged portion 10 forms the bend in the completed L. The tube 2 is then removed from the dies 3 and 4 and bent into U-shaped form, as shown in Figure 4. This bending is preferably accom-

plished by two mandrels 11 which are inserted in the open ends of the tube and are then brought together parallel around a spacer bar 12, as shown in Figure 4, whereby the two parallel legs 13 of the L are formed. 60 The legs 13 may be threaded as desired, as shown in Figure 5, if the L is to be used for threaded pipe. There are no seams whatever in the L. The legs 13, the bend portion 14 and the bridge portion 15 of the L are 65 all drawn from the seamless tubing 2 by forging operations.

The present invention is not limited to the illustrated details but may be otherwise embodied within the scope of the following 70 claims.

I claim:

1. The method of making return L's from tubing, comprising forming a bulge on one side of the tube and then bending the tube 75 in the opposite direction so as to form the two parallel legs of the L, substantially as described.

2. The process of manufacturing return L's from tubing, which consists in placing a 80 length of tubing in dies having a cavity at one side of the tube and compressing the tube longitudinally so as to cause the metal to flow into said cavity thereby forming a bulge on one side of the tube, and then bending 85 the ends of the tube parallel to each other so as to form the legs of the L, substantially as described.

3. The process of making return L's from tubing, which consists in compressing a 90 length of tubing longitudinally and simultaneously forming a bulge at one side of the tube, and then bending the ends of the tube in the opposite direction to form the parallel legs of the L, substantially as described. 95

4. The process of making return L's from tubing, comprising placing a length of tubing within dies having a cavity at one side of the tubing, inserting plungers in the open ends of the tubing, and bringing them towards each other so as to longitudinally compress the tubing, whereby the tube is caused to bulge into said cavity, and thereafter bending the tube into U-shaped form around a spacer member while preventing collapsing 105 of the end portions of the tube, substantially as described.

5. The process of making return L's from tubing, which consists in placing a length of tubing within dies having a cavity at one 110

side of the tubing, inserting plungers in the open ends of the tubing and bringing them toward each other so as to longitudinally compress the tubing, whereby the tube is caused to bulge into said cavity, and thereafter bending the ends of the tube in a direction away from the bulge so as to form the parallel legs of the L, substantially as described.

10 6. The process of making return L's from tubing, which consists in placing a short length of tubing having one side longer than

the other within dies having a cavity at the longer side of the tube, and compressing the tube longitudinally so as to cause the metal of the longer side of the tube to flow into said cavity, and thereafter bending the ends of the tube in the direction away from the bulge so as to form the parallel legs of the L, substantially as described. 15

In testimony whereof, I have hereunto set my hand.

EDWIN E. SLICK.
